UNITED STATES PATENT OFFICE.

GEORG GRUSSENDORF, OF HANOVER, GERMANY.

PUMP.

No. 892,150.

Specification of Letters Patent. Patented June 30, 1903.

Application filed March 28, 1907. Serial No. 365,169.

To all whom it may concern:

Be it known that I, GEORG GRUSSENDORF, citizen of Germany, residing at Hanover, Germany, have invented certain new and useful Improvements in Pumps; and I do hereby declare the following to be a full, clear, and exact description of the invention, such as will enable others skilled in the art to which it appertains to make and use the same.

There are pumps known which elevate liquid from pump barrels in delivery pipes by means of compressed air, the action of which can be controlled by mechanism located at any distance from the liquid to be elevated. These pumps consist essentially of two pump barrels arranged at the bottom of the well and provided each with an ordinary check or flap valve, which closes by its own weight.

The above-mentioned barrels are alternately supplied with compressed air, so that the liquid contained in the barrels is elevated to any height corresponding to the pressure available. As these pumps with the usual flap valves have not proved satisfactory on account of the unreliability of the valves, the arrangement is made according to the present invention as follows:

The drawing Figure 1 represents a pumping plant according to the present invention, the pump barrels of which are provided with flap valves closed and opened automatically by the driving medium itself. Fig. 2 represents another constructive form of the arrangement for opening and closing the valves.

The driving medium, viz., compressed air, steam or gas, which is generated in the usual manner by a pneumatic pump, boiler or the like—and which is not shown in the drawing—is conducted in pipes to a valve distribution apparatus consisting of the valves C_1, C_2, C_3, C_4 (Fig. 1). These valves are connected in a convenient manner with one or two pump barrels d_1, d_2 by means of pipes (Fig. 1).

The plant, according to Fig. 1 shows the valve of the barrel d_1 and opened automatically by the compressed air, steam or gas itself. For this purpose the valve stem at its lower extremity is connected in a convenient manner with the levers f and g , which are actuated by means of the diaphragms h and i (or, if desired by pistons) standing alternately under the pressure of the pressure fluid. The above-mentioned diaphragms as well as their chambers and the levers f and g are located in a water-proof foundation box and all openings in the cover-plate for the

pneumatic feed pipes are made with hermetical joints and the opening for the valve stem is provided with a stuffing-box. The above-mentioned diaphragms consist preferably each of an unperforate disk of leather covered on both sides with a layer of soft india rubber or impregnated with india rubber or other water-proof material. They can be reinforced by two or several disks of this kind, combined in one.

The supplying of the pump barrels in due time with compressed air as well as exhausting the same in succession is effected by the distributing valves C_1, C_2, C_3 and C_4 as shown in Fig. 1, which are actuated by the shaft k provided with cams adapted to the purpose. The stem m of each of these valves protrudes somewhat downwards from the interior valve chamber to the cam surface and reaches upwards close to a flexible diaphragm, which is similar to the above-mentioned diaphragms, and which divides the valve into two isolated chambers, allowing however, on account of its flexibility, an external pressure exercised by the stem upon the exterior side of the diaphragm to be transferred to the valve in order to open the same.

The above-mentioned cams on the shaft k are arranged in such a manner that the valves C_1, C_3 and the valves C_2 and C_4 are opened during a shorter or longer period alternately in conformity with the required admission or blowing-off of the compressed air.

Fig. 2 represents another form of construction with one pump barrel, the flap valve (e) of which is opened and closed by two diaphragms arranged above the barrel, so that the diaphragms can be placed above the level of the liquid. For this purpose the rods p and q are moved by the diaphragms and are provided with the cross-heads t , u ; another head v is secured to the valve stem r , by means of a pivot link, such as a ball and socket joint or the like. These cross-heads are connected by two or more connecting-rods w . The rods p and q and the valve stem r are guided in a convenient manner in transverse connecting pieces.

Simple plants with only one pump barrel need not absolutely have two diaphragms; one of the latter may be omitted, if the valve is closed by spiral spring d_4 or weight. The arrangement of two diaphragms, however, is always preferable, as the valve is closed by such a diaphragm with a stronger pull than the pressure exercised by the compressed air

upon the head of the valve, so that small leakages of the joint will not injuriously affect the good working of the valve. A greater reliability of the working of the pump 5 is therefore obtained by the arrangement of two diaphragms as shown in the drawings.

The working of the present pump, the barrel of which and the delivery pipe are to be filled with liquid before the beginning of 10 the operation, may be effected in such a manner that the compressed air after having forced the liquid from one barrel into the delivery pipe is either immediately blown-off in a reverse direction or utilized to partially fill 15 the other barrel and pneumatic supply-pipes.

The above mentioned distributing-valves have the advantage over ordinary distributing-valves, that they close not only by spring or weight but also by the driving-medium 20 itself causing thus a reliable joint, while the interior valve chamber is closed hermetically by the above-mentioned closing-diaphragm. Besides, these valves need little or no attention and are cheap and simple.

25 In order to protect the diaphragms from the corrosive effect of the steam the chamber containing the diaphragms as well as the interior chambers of the distributing-valves can be filled with glycerin.

30 Claims:

1. In a pump, two barrels situated below the water level, each having an inlet and an outlet, an inwardly opening valve in each barrel between the inlet and outlet, fluid actuated means to mechanically operate the 35 valve, a pressure fluid supply, feed pipes each leading from the fluid supply to one of the barrels on the discharge side of its valve and to the valve closing mechanism for said 40 barrel and to the valve opening mechanism of the other barrel, distributing valves arranged to supply pressure fluid to the said feed pipes alternately, and means arranged 45 to operate at predetermined fixed intervals to control the distributing valves.

2. In a pump, two barrels situated below the water level, each having an inlet and an outlet, an inwardly opening valve in each 50 barrel between the inlet and outlet and below the latter, fluid actuated means to mechanically open and close the valve, a pressure fluid supply, feed pipes leading from the fluid supply to each of the barrels on the discharge side of its valve and to its valve operating mechanism, exhaust pipes leading from each barrel and valve operating mechanism, 55 distributing valves arranged to control the supply of pressure fluid to said feed pipes, exhaust valves arranged to control the exhaust pipes, and means operating independently of the pump supply and discharge to 60 actuate the distributing and exhaust valves to simultaneously supply pressure fluid to one barrel and exhaust the fluid from the

other barrel while holding the one valve 65 closed and the other valve open.

3. In a pump, two barrels situated below the water level, each having an inlet and an outlet, an inwardly opening valve in each barrel between the inlet and outlet, valve 70 operating mechanism for each barrel comprising fluid pressure chambers, diaphragms, levers having one arm operated upon by a diaphragm, and a connection between the levers and the valve to mechanically open 75 and close said valve according as the pressure fluid is introduced to one or the other diaphragm chamber, a pressure fluid supply, a feed pipe leading from the pressure fluid supply to each barrel on the discharge side of 80 its valve and to a diaphragm chamber of its valve operating mechanism and to the opposite diaphragm chamber of the other valve operating mechanism, distributing valves arranged to control the inlet to each of the feed 85 pipes, exhaust pipes leading from each barrel and from its valve operating mechanism, exhaust valves controlling the discharge from the exhaust pipes, cams arranged to actuate the distributing valve of one barrel and the 90 exhaust valve of the second barrel and then the distributing valve of the second barrel and the exhaust valve of the first barrel.

4. In a pump, two barrels situated below the water level, each having an inlet and an 95 outlet, an inwardly opening valve in each barrel between the inlet and outlet, valve operating mechanism for each barrel comprising fluid pressure chambers, diaphragms, levers having one arm operated upon by a 100 diaphragm, and a connection between the levers and the valve to mechanically open and close said valve according as the pressure fluid is introduced to one or the other diaphragm chamber, a pressure fluid supply, a 105 feed pipe leading from the pressure fluid supply to each barrel on the discharge side of its valve and to a diaphragm chamber of its valve operating mechanism and to the opposite diaphragm chamber of the other valve 110 operating mechanism, distributing valves arranged to control the inlet to each of the feed pipes, exhaust pipes leading from each barrel and from its valve operating mechanism, exhaust valves controlling the discharge 115 from the exhaust pipes, the distributing valves and exhaust valves held closed by diaphragms under the influence of pressure fluid, and cams acting upon the stems of the distributing and exhaust valves to open said 120 valves against the pressure fluid, said cams arranged to actuate the distributing valve of one barrel and the exhaust valve of the second barrel and then the distributing valve of the second barrel and the exhaust valve of 125 the first barrel.

5. In a pump for elevating liquid by fluid pressure, a barrel situated below the water

level and having an inlet and an outlet, an inwardly opening inlet valve interposed between the inlet and outlet, inlet valve operating means comprising a diaphragm device 5 comprising two diaphragms each located in a closed chamber, a mechanical connection between each of the diaphragms and the inlet valve, a pressure fluid supply, feed pipes leading from the fluid supply to the barrel on the discharge side of the valve and to each of the diaphragms, distributing valves arranged to direct the pressure fluid alternately on the one hand to the interior of the barrel and to the diaphragm chamber to close the inlet valve and on the other hand to the diaphragm chamber to open the inlet valve.

6. In a pump for elevating liquid by fluid pressure, a barrel situated below the water level and having an inlet and an outlet, an inwardly opening inlet valve interposed between the inlet and outlet, inlet valve oper-

ating means comprising a diaphragm device consisting of two members, a mechanical connection between each of the diaphragm members and the inlet valve, a pressure fluid supply, feed pipes leading from the fluid supply to the barrel on the discharge side of the valve and to each of the diaphragms, distributing valves arranged to direct the pressure fluid alternately on the one hand to the interior 25 of the barrel and to the diaphragm chamber to close the inlet valve and on the other hand to the diaphragm chamber to open the inlet valve.

In testimony whereof I hereunto affix my 30 signature in the presence of two witnesses.

GEORG GRUSSENDORF.
